(57) **CLAIM**

The ornamental design for a computer display system or portion thereof showing an animated graphical user interface having a three dimensional appearance as shown and described.

DESCRIPTION

FIG. 1 is a front view of a computer display system or portion thereof showing a first image of an animated graphical user interface having a three-dimensional appearance showing the claimed design; and, FIG. 2 is a second image thereof.

The peripheral broken lines in the figures show the computer display system or portion thereof, and form no part of the claimed design.

The other broken lines in the figures show a three dimensional environment within a field of view of the user and portions of the animated graphical user interface that form no part of the claimed design.

The appearance of the animated image sequentially transitions between the images shown in FIGS. 1-2. The process or period in which one image transitions to another forms no part of the claimed design.
